ELEVATOR

Filed Nov. 9, 1929

UNITED STATES PATENT OFFICE

GERALD R. HUNT, OF LOS ANGELES, CALIFORNIA

ELEVATOR

Application filed November 9, 1929. Serial No. 406,026.

This invention relates to an elevator for handling well drilling tools and equipment. Elevators are employed in well drilling rigs for handling drill pipe, casing, etc., and are used more particularly for suspending lengths of pipe, or the like. The usual method of employing an elevator is to operate it vertically in the well derrick through a line and traveling block. An operator is positioned in an elevated place in the derrick and swings the elevator into position around the upper portion of a vertically arranged part, such as a length of drill pipe, and swings the door or gate of the elevator shut. This arranging of the elevator around the pipe is often done when the elevator is in motion. In the event that the door or gate of the elevator is not securely latched or locked, the elevator may engage a pipe coupling, or other projecting part on the pipe, and raise the pipe some distance, and then, through lateral shifting or other cause, the coupling may slip from the elevator and let the pipe fall to the floor of the derrick. As the lengths of pipe or casing are very heavy, considerable damage is done when such a part drops or falls as described above.

It is a general object of the invention to provide an elevator in which the body of the elevator is shifted outwardly from a coupling, or the like, on the drill pipe, casing, or other part to be handled by the elevator, to a position where the coupling will not be engaged and lifted by the elevator, in the event the door or gate is not latched.

Another object of the invention is to provide an elevator of the character mentioned in which the body of the elevator may be freely arranged around the part to be handled by the elevator without any resistance.

It is another object of the invention to provide an elevator of the character mentioned in which the means for holding the elevator from the coupling on the part to be handled does not require manual operation or setting.

Another object of the invention is to provide a construction in the form of an attachment that may be embodied on or applied to any suitable form of side door elevator to operate as above mentioned.

It is a further object of the invention to provide a construction of the character mentioned which embodies a minimum number of parts and is particularly simple and inexpensive of manufacture.

Another object of the invention is to provide a construction of the character mentioned in which the coupling engaging part may be set or latched out of operation when desired.

Other objects and features of the invention will be best and more fully understood from the following detailed description of a typical form and application of the invention, throughout which description reference is had to the accompanying drawings, in which:

Fig. 1 is a side elevation of an elevator embodying the present invention, illustrating a length of casing extending through it and showing it in the open position. Fig. 2 is a top or plan view taken as indicated by line 2-2 on Fig. 1. Fig. 3 is an enlarged vertical detailed sectional view, being a view illustrating the position of the device before the elevator has engaged the coupling. Fig. 4 is a view similar to Fig. 3 showing the upper side of the elevator engaging the coupling. Fig. 5 is a horizontal detailed sectional view of the coupling engaging arm. Fig. 6 is a vertical detailed sectional view illustrating the arm in a retracted position.

In the drawings I have illustrated the invention as embodied in a typical form of elevator and will consider the elevator as being adapted to handle a length of casing 10 having a coupling 20 at its upper end. As the invention may be embodied in various forms of side-door elevators for handling various well drilling tools or equipment, it is not to be considered as limited to the particular form of elevator about to be described or to the particular form of well drilling tool or part which the elevator is adapted to handle.

The device provided by this invention includes, generally, an elevator 11 having a body section 12 and a gate or door section 13, a bracket 14 on the elevator, an arm 15 pivotally attached to the bracket 14, means 16 normally yieldingly urging the arm 15 into a position where it is adapted to engage a part

such as the coupling 20 on the casing, and means 17 for setting the arm 15 in a retracted position.

The elevator in which the present invention is embodied may be any suitable type of side-door elevator and may be adapted to handle various well drilling parts such as drill pipe, casing, sucker rods, etc. The form of elevator illustrated in the drawings is a simple type of side-door elevator which I will consider as adapted to handle the casing 10. The main section 12 of the elevator may be of substantially U-shaped configuration having an opening 18 to receive the casing 10. The inner portion of the opening 18 is preferably curved to conform to the configuration of the casing. The upper end or side 19 of the main section 12 is preferably made flat to receive or support the coupling collar 20, or like projecting part, on the casing 10. Projecting bail ears 21 are provided on opposite sides of the main section 12 to receive bails 22 for carrying the elevator.

The door or gate section 13 is pivotally attached to one of the side parts of the main section and is in the nature of a closure adapted to extend across the open side of the opening 18. The gate section 13 is pivotally attached or mounted on the side part 23 of the main section 12 by a vertical pivot pin 24. The inner side of the gate section 13 is preferably curved to conform to the configuration of the casing 10. A latch 25 is provided on the gate section 13 to engage a lug 26 on the main section 12. The latch 25 is pivoted on the exterior of the gate section and is adapted to engage the lug 26 to retain the gate section in the closed position. In the particular form of elevator shown the latch 25 is normally yieldingly urged by a spring 27 into a position to automatically cooperate with the lug 26 when the gate section 13 is swung into the closed position. The latch 25 is provided with a handle 28 which acts as a means for releasing the latch as well as a means for shifting the gate section.

The bracket 14 is provided to carry the arm 15 and projects above the top or upper side 19 of the main section. The bracket 14 may be of various constructions, depending upon the particular elevator to which it is attached or on which it may be formed. In the particular case shown the bracket 14 is in the nature of an attachment and is in the form of a simple unitary part to be vertically arranged at the exterior of the main section 12 of the elevator. The bracket 14 is preferably an elongated part and extends from the lower side of the main section and projects from the upper edge of the section. The bracket 14 is preferably centrally located on the section so that it is directly opposite the center of the gate section 13, when the gate section is closed or latched. The bracket 14 may have a curved inner side to seat against the

curved exterior of the main section 12 of the elevator and may be attached to the elevator by spaced studs 30. The bracket 14 is preferably of heavy construction and projects a substantial distance above the upper side 19 of the section 12. An inwardly projecting flange 31 is provided on the bracket 14 to seat against the upper side 19 of the elevator section 12. The upper portion of the bracket 14, that is, the portion projecting above the elevator, may be curved inwardly or toward the center of the elevator.

The arm 15 is provided to engage the coupling 20 in such a manner as to hold the elevator spaced from the casing so that the elevator does not engage the lower side of the coupling unless the gate section is in the latched position. The arm 15 depends from the upper end of the bracket 14 and is preferably pivotally attached to the bracket. In the preferred form of the invention the upper end of the bracket 14 is provided with yoked portions 32 and the upper end of the arm 15 extends between the portions 32. A pivot pin 33 extends between the yoked portions 32 and pivotally mounts the arm 15 on the bracket. The arm 15 extends downwardly and its lower end is spaced a short distance above the upper side 19 of the section 12. The lower end of the arm is preferably normally adjacent the edge of the opening 18. The lower portion or the coupling engaging portion of the arm 15 is preferably comparatively wide and its inner side 34 is curved to effectively slide over the coupling when the gate section is latched and to engage the coupling when the gate is open or unlatched. In the particular case shown the lower portion of the arm 15 is of curved cross section, as clearly shown in Fig. 5 of the drawings.

The means 16 is provided to yieldingly urge the lower portion of the arm 15 inwardly, to a position where it will engage the coupling. The means 16 operates to normally resist inward movement of the arm 15, when engaged by the coupling, so that the elevator is held away from the coupling 20 a sufficient distance to allow the elevator to be raised over the coupling in the event the gate 13 is not latched. The means 16 includes a spring 35 arranged under compression between the outer side of the arm 15 and the bracket 14. In accordance with the invention, means is provided for guiding the spring 35 and for holding the spring against displacement. A guide stem 36 is pivotally attached to the outer side of the arm 15 and slidably extends through an opening 37 in the bracket 14. Spaced lugs 38 are provided on the outer side of the arm 15 a short distance above the lower end of the arm and the end of the guide stem 36 extends between the lugs. A pivot pin 39 extends between the lugs 38 and pivotally secures the stem 36 to the arm. The opening 37 is sufficiently large to freely pass

the stem 36 and to allow for a certain amount of vertical movement of the stem. The stem 36 projects outwardly from the bracket 14, and an adjusting nut 40 may be screw threaded on the end of the stem. The nut 40 acts to prevent the stem 36 from becoming displaced in the opening 37 and limits the inward movement of the arm 15. The spring 35 surrounds the stem 36 and extends over the lugs 38 which act to center the end portion of the spring. The spring 35 is sufficiently strong to offer considerable resistance when the arm 15 is swung outwardly.

The means 17 is provided to set or lock the arm 15 in a retracted position where it will be free of the coupling 20. The means 17 includes a shoulder 50 on the stem 36. The shoulder 50 is provided intermediate the ends of the stem 36 and is adapted to seat against the outer side of the bracket 14. In the case illustrated the shoulder 50 is in the nature of the end wall or end of a notch 51 formed on the lower side of the stem 36. The shoulder 50 is substantially vertical and the notch 51 is formed to receive the lower wall of the opening 37. When it is desired to set the arm 15 in the retracted position, the arm is forced outwardly until the notch 51 receives the lower portion of the opening 37 and the shoulder 50 engages the outer side of the bracket 14.

It is believed that the operation of the device provided by this invention will be apparent from the foregoing detailed description. It is to be noted that the device is particularly simple of construction and is effective in preventing the elevator from engaging and lifting the coupling 20 in the event the gate 13 is not latched when the elevator is operated upwardly. In employing the elevator construction provided by this invention, the elevator is swung or arranged around the casing 10 in the usual manner. If the gate section 13 is latched when the elevator is arranged on the casing, the arm 15 engages the coupling and is forced outward when the elevator is raised. In the event the gate section is not properly latched, the arm strikes the coupling 20 and the spring 35 is sufficiently strong to prevent the arm from being forced outward relative to the elevator, and the elevator is shifted bodily outward so that it does not engage the bottom of the coupling. In this manner the elevator is positively prevented from raising the casing if the gate 13 is not latched. It is to be noted that the arm 15 may be forced outwardly relative to the elevator when the gate is latched, to a position where the coupling 20 is free to seat against the upper side 19 of the elevator. The invention may be embodied in a single unitary structure or attachment as shown in the drawings, and may be proportioned so that it is adapted to

be used in connection with various forms of elevators.

Having described only a typical, preferred form of my invention, I do not wish to limit myself to the specific details set forth, but wish to reserve to myself any changes or variations that may appear to those skilled in the art or fall within the scope of the following claims.

Having described my invention, I claim:

1. In an elevator, a main section, a gate section, and means on the main section adapted to hold the elevator spaced from a projection on a part extending through the elevator.

2. An elevator of the character described including, a main section having an opening, a gate section adapted to close the opening, and means on the main section for holding the main section spaced from a projection on a part extending through the opening when the gate section is open.

3. An elevator of the character described including, a main section having an opening, a gate section adapted to close the opening, and spring means on the main section for holding the main section spaced from a projection on a part extending through the opening when the gate section is open.

4. An elevator of the character described including, a main section having an opening, a gate section adapted to close the opening, and means for holding the main section spaced from a projection on a part extending through the opening when the gate section is open, including an arm carried by the main section.

5. An elevator including, a main section having an opening adapted to engage around a part, a gate section adapted to retain a part in the opening, means for holding the main section spaced from a projection on a part extending into the opening when the gate section is open including, an arm pivoted to the main section, and means yieldingly urging the arm toward the central longitudinal axis of the opening.

6. An elevator including, a main section having an opening adapted to engage around a part, a gate section adapted to retain a part in the opening, means for holding the main section spaced from a projection on a part extending into the opening when the gate section is open including, an arm pivoted to the main section, and a spring normally yieldingly urging the arm toward the axis of the opening.

7. An elevator including, a main section having an opening adapted to engage around a part, a gate section adapted to retain a part in the opening, and means for holding the main section spaced from a part extending into the opening when the gate section is open including, a bracket projecting from the main section, an arm pivotally attached

to the bracket, and means yieldingly urging the arm toward the axis of the opening.

8. An elevator including, a main section having an opening adapted to engage around a part, a gate section adapted to retain a part in the opening, and means for holding the main section spaced from a projection on a part extending into the opening including, a bracket projecting above the main section, an arm pivotally attached to the bracket and depending from the bracket, and a spring yieldingly urging the lower portion of the arm toward the axis of the opening.

9. An elevator including, a main section having an opening adapted to engage around a part, a gate section adapted to retain a part in the opening, and means for holding the main section spaced from a projection on a part extending into the opening when the gate is open including, a bracket projecting above the main section, an arm pivotally attached to the bracket and depending from the bracket, and a spring between the bracket and the arm yieldingly urging the lower portion of the arm toward the axis of the opening.

10. An elevator including, a body having an opening adapted to engage around a part, a gate adapted to retain a part in the opening, and means holding the body spaced from a projection on the part in the opening when the gate is in the open position, said means including, a bracket projecting from the body, an arm depending from the bracket, and a compression spring between the arm and bracket.

11. An elevator including, a body having an opening adapted to engage around a part, means for retaining the part in the opening, means for holding the body spaced from a projection on a part in the opening when the retaining means is not in operation, and means for holding the last-mentioned means against operation.

12. An elevator including, a body having an opening adapted to engage around a part, means for retaining the part in the opening, means for holding the body spaced from a projection on a part in the opening when the retaining means is unactuated including, a pivotally mounted arm, and a spring urging the arm toward the axis of the opening, and means holding the spring against operation.

13. An elevator including, a body having an opening adapted to engage around a part, means for retaining the part in the opening, means for holding the body spaced from a projection on a part in the opening when the retaining means is inoperative including, a pivoted arm, a spring urging the arm toward the axis of the opening, and a guide stem on the arm, and means holding the spring against operation including a shoulder on the stem adapted to engage a fixed part.

14. An elevator including, a body having

an opening adapted to engage around a part, means for retaining the part in the opening, means for holding the body spaced from a projection on a part in the opening when the retaining means is inoperative including, a pivoted arm, a spring urging the arm toward the axis of the opening, a guide stem on the arm, an adjustable part on the stem to limit movement of the arm, and means holding the spring retracted including a shoulder on the stem.

15. An attachment for an elevator adapted to engage around a member which includes, a bracket adapted to be attached to the elevator, an arm pivoted to the bracket, and means yieldingly urging the arm against a projection on a member extending into the elevator.

16. An attachment for an elevator adapted to engage around a member which includes, a bracket adapted to be attached to the elevator, an arm pivoted to the bracket, and means yieldingly urging the arm against a projection on a member extending into the elevator including a spring arranged between the bracket and the arm.

In witness that I claim the foregoing I have hereunto subscribed my name this 28th day of October, 1929.
